BRAUN TUBE

Bruno Wienecke, Berlin, Germany, assignor to
Radicaktiengesellschaft D. S. Loewe, Berlin-
Steglitz, Germany, a company of Germany

Application June 3, 1933, Serial No. 674,204
In Germany June 8, 1932

8 Claims. (Cl. 250—27.5)

It has been found that, particularly when employing high-emission cathodes of the metallic vapour type, it is necessary to outgas the parts of the system very carefully, preferably before application of the emissive coating.

The subject matter of the invention is a Braun tube, the system of which is constructed and arranged in such fashion that all parts of the system are outgassed, possibly wholly independently of each other, and the application of the metal by atomization may be performed after completion of the outgassing process. At the same time the system comprising cathode, Wehnelt cylinder and anode is constructed, in accordance with the invention, in such fashion that centering upon the assembly takes place automatically. For this purpose all parts of the system—insofar as the same are not held together by direct attachment—are guided or secured to common guide members or the like. The individual parts of the system are furnished with a cross-section, the form and size of which is such that they contain a magnetic flux adequate for heating to the outgassing temperature. Those parts, the cross-section of which is relatively small, so that the same alone cannot be raised to the requisite temperature without overheating of the adjacent parts of larger cross-section, are secured, in accordance with the invention, to auxiliary plates, which may be raised readily to a high temperature by eddy current heating, and at the same time, by the conduction of heat, assist considerably towards heating of the parts of smaller cross-section. The system, in accordance with the invention, is constructed as a pot system closed off completely towards the rear and the sides, so that spreading effects are unable to take place. The high-emission metal to be atomized is, in accordance with the invention, atomized by directed evaporation, so that the same strikes in the main against the cathode. By reason of the particular form of the system the formation of conductive layers of the atomized metal outside of the system is completely avoided.

In the drawing a form of embodiment of the tube according to the invention, and also certain details, are shown by way of example, in part diagrammatically.

Fig. 1 shows the complete arrangement, while in

Fig. 2 there is shown the system comprising cathode, Wehnelt cylinder and anode, in

Fig. 3 the cathode of the system, in

Fig. 4 the pair of deflecting plates, and in

Fig. 5 the insulating holding means for the high-potential anode.

In the drawing 1 is the bulb of the Braun tube having the pinch 29, to which there may be secured the holding means 2 for the pairs of deflecting plates 4 and 5, for example by means of the band 23. Naturally it is also possible, particularly when employing a pinch having a very large surface, to fuse the holding means 2 into the pinch itself. In this case the holding means 5 may consist of a stable metal tube having a relatively large thickness of wall and small diameter, fused into the pinch, and of the actual holding portion, which may be connected with the fused-in holding tube by introducing it into or slipping 10 it over the same or by welding. The actual system producing the cathode ray consists of the Wehnelt cylinders 10, 11, with the cathode 17, the screening anode 18 and the high-potential anode 21. The Wehnelt cylinder in accordance with 15 the invention may consist of a cylinder of relatively small diameter 10, which is connected with a plate 9 of larger diameter and, by means of the intermediate cover 27, with the cylinder 11 of larger diameter. The cathode 17—as shown 20 more particularly by Fig. 3—is introduced into a metallic part 14 by means of an insulating tube. The part 14 may naturally be constructed as a massive cylinder. It has been found convenient, however, to construct the same—in order to 25 diminish its heat capacity as far as possible—for example in the form shown. The cathode 17 is finally mounted with its leads 15, 16 in the part 14, and the part 14 is then simply introduced into the cylinder 10. The holding plate 9 of the system is guided, for example, by borings, preferably on three metallic holding devices 3, which are fused into the pinch either in direct fashion, or preferably—for increasing the stability—with the inclusion of transverse members. The 30 Wehnelt cylinder 11 is closed off at the front by the mica disc 20, which is furnished with an aperture of relatively small diameter, and on the inner side of which there is arranged the screening anode 18. At a relatively slight distance 35 from the insulating disc 20 there is arranged the main anode 21 with the current lead 22 and the lead 23. The mica disc 20 in the same manner as the high-potential anode 21 and the system-supporting plate 9 is secured to the holding 40 means 3. The supply of potential to the Wehnelt cylinder takes place via the holding means 3, and the supply of potential to the screening anode 18 over a lead not shown in the drawing and insulated against the Wehnelt cylinder by means 45 50 55

of the mica disc 20. In order to screen off the interior of the Wehnelt cylinder as completely as possible against the field of the high-potential anode the diameter of the screening anode 18 must be as large as possible. The same is preferably so dimensioned that the distance between the wall of the Wehnelt cylinder and the screening anode amounts to 1 mm. or less. Were the screening anode to rest immediately against the mica disc 20, conductive bridges would be able to form between the anode and the Wehnelt cylinder on the sheet of mica upon the atomization of the light metal provided in the capsule 12 with the tube fitting 13. To ensure that the possibility of a conductive connection of this nature between the screening anode and the Wehnelt cylinder is precluded, there may be provided, in accordance with the invention, between the screening anode 18 and the mica plate 20 a distance disc 19, which preferably possesses a considerably smaller diameter than the anode 18. Naturally this distance plate may consist equally well of insulating material or metal. It has been found convenient, however, to make the two discs 18 and 19 of the same metal. The high-potential anode 21 requires to be insulated electrically against the holding means 3.

The assembly of the system may be performed in the following manner. At first the cathode portion 14 with the completely mounted cathode 17 is introduced into the cylinder 10 connected with the disc 9, and the disc 9 fitted over the holding means 3 and secured to the same, for example by welding. There is then fitted the intermediate cover 27, and on the latter the cylinder 11. Naturally the cylinder 11 and/or the cover 27 may also be furnished with abutments which are likewise guided on the holding means 3. The insulating plate 29, which is also guided on the holding means 3 and to the inner side of which there is secured the anode 18 with the intermediate member 19, is thereupon fitted. Over the holding means 3 there are then slipped insulating tubes 26 (Fig. 5). On the insulating tubes 26 there are fitted insulating tubes 24, and then the anode slipped over, the insulating tubes 24 fitted on, and the whole secured in immovable fashion with the assistance of the plug 25, since all parts are secured to the same holding means 3, centering takes place automatically. It has been found that upon the assembly according to the invention subsequent centering is unnecessary.

The cathode may preferably be constructed as an indirectly heated, pointed cathode (preferably: barium oxide-barium cathode). It has been found that for proper working of the tube it is important to dimension correctly the spacing between the cathode and the cylinders 10 and 11. The distance of the cathode point from the edge surface of the cylinder 10 should preferably amount to approximately 1-3 mm., and the distance from the surface of the cylinder edge 11 to approximately 3-10 mm., assumed the potential of the cylinder is -100- -300 and the potential of the screening anode 18 approximately +100- +500 volts.

As shown more particularly by Fig. 2, the metal to be atomized is arranged in a capsule 12, which is connected with the interior of the cylinder by the tube 13, and may be raised by eddy current heating to the temperature necessary for atomization of the metal independently of the other parts of the system.

As shown in Fig. 4, the deflecting plates 4 and

5 are preferably given such a form that they may be raised alone by eddy current to the outgassing temperature. In this connection semi-cylindrical form has been found particularly convenient. In order to avoid safely distortion of the plates during the outgassing heating process, it is necessary to employ relaxed material. The deflecting plates 4 may conveniently be secured to a circular holding device 6, which in turn is attached to holding means 2. The one plate is in 10 conductive connection with the holding means 2 (which may be maintained at anode potential), whilst the second plate, to which there is conducted the control potential over the line 8, is insulated against the holding means by the insulating plate 7.

Naturally it is quite readily possible to modify details of the arrangement. In particular it is possible to secure also the deflecting plates to the same holding means as the system producing 20 the cathode ray, so that the centering of the deflecting plates in relation to the system also takes place automatically upon the assembly.

If the tube according to the invention is to be employed more particularly for television purposes as tube with light control, the screening anode may be used as control electrode. Naturally, however, it is also possible in this case to provide a special control grid within the dark space of the cathode, which grid if necessary 30 may be screened off against the Wehnelt cylinder by a screening grid raised to a suitable potential.

In place of a pointed cathode it is naturally also possible to employ any other desired cathodes, such, for example, as cathodes with 35 meandrian emissive surface and the like. It is furthermore possible, in place of barium oxide-barium cathodes, which are produced preferably by atomizing barium on to a smeared oxide cathode, also to employ cathodes which may be 40 produced by atomizing barium or another light metal on to a tungsten dioxide base. The essential feature in each case is that the arrangement of the single parts is such that the application to the cathode by atomization may be performed 45 after the outgassing of the system.

I claim:

1. A Braun tube comprising a press, an envelope sealed to said press, a plurality of rod-shaped supporting members secured to said press 50 and extending in a direction parallel to the axis of said tube, a cathode, an assembly of electrodes comprising a plurality of cylinder-shaped members disposed co-axially with said tube and a plurality of apertured plate anodes disposed 55 perpendicular to the axis of said tube, a plurality of supporting plates having guiding holes corresponding in number and situation to said supporting members, each of said supporting plates being attached to an electrode of said 60 assembly, said supporting members projecting through said guiding holes and locating the electrodes of said assembly in position, and deflecting means supported from said press.

2. A Braun tube comprising a press, an envelope sealed to said press, a plurality of rod-shaped supporting members secured to said press and extending in a direction parallel to the axis of said tube, an assembly of electrodes comprising a plurality of cylinder-shaped members disposed co-axially with said tube, a cathode, and a plurality of apertured plate anodes disposed 70 perpendicular to the axis of said tube, a metallic cathode holder locating said cathode in position with respect to one of said cylinder-shaped mem- 75

bers and inside thereof and being insulated from said cathode, a plurality of supporting plates having guiding holes corresponding in number and situation to said supporting members, each 5 of said supporting plates being attached to an electrode of said assembly, said supporting members projecting through said guiding holes and locating the electrodes of said assembly in position, and deflecting means supported from said 10 press.

3. The invention set forth in claim 1, and wherein said assembly of electrodes comprises an anode which is provided, in the same manner as said supporting plates, with guiding holes 15 corresponding in number and situation to said supporting members, said supporting members projecting also through said guiding holes in said anode and locating said anode in position relatively to the remaining parts of said assembly. 20

4. A Braun tube including a Wehnelt cylinder including at least one hollow cylindrical portion, a metallic cathode holder mounted inside said Wehnelt cylinder and having at least one cylindrical portion, the outer diameter of which is 25 equal to the inner diameter of said hollow cylindrical portion, said second mentioned cylindrical portion having its outer surface located adjacent to the inner surface of said hollow cylindrical portion for axially aligning said cathode holder with said Wehnelt cylinder, and a thermionic 30 cathode supported and positioned in said Wehnelt cylinder by and insulated from said cathode holder, said cathode having an emissive surface located symmetrically in relation to the axis of 35 said second mentioned cylindrical portion.

5. A Braun tube comprising a press, an envelope sealed to said press, a fluorescent screen, a Wehnelt cylinder including at least one hollow cylindrical portion, a metallic cathode holder 40 mounted inside said Wehnelt cylinder and having at least one cylindrical portion the outer diameter of which is equal to the inner diameter of said hollow cylindrical portion, said second mentioned cylindrical portion having its outer surface located adjacent to the inner surface of said hollow cylindrical portion for axially aligning said cathode holder with said Wehnelt cylinder, and a thermionic cathode supported and positioned in said Wehnelt cylinder by and insulated from said cathode holder, said cathode 45 having an emissive surface located symmetrically in relation to the axis of said second mentioned cylindrical portion, at least one anode mounted in operative relationship to said cathode, two pairs of deflecting plates mounted between said anode and said screen, and a plurality of metallic 50 holders attached to said press, said metallic holders supporting said Wehnelt cylinder having said cathode positioned therein by means of said cathode holder and all of the other said electrodes.

6. A Braun tube including a Wehnelt cylinder including at least one hollow cylindrical portion, a metallic cathode holder mounted inside said 55 Wehnelt cylinder and having at least one cylindrical portion the outer diameter of which is equal

to the inner diameter of said hollow cylindrical portion, said second mentioned cylindrical portion having its outer surface located adjacent to the inner jacket surface of said hollow cylindrical portion for axially aligning said cathode holder with said Wehnelt cylinder, and a thermionic cathode supported and positioned in said Wehnelt cylinder by and insulated from said cathode holder, said cathode having an emissive surface located symmetrically in relation to the axis of 10 said second mentioned cylindrical portion, and a metallic holding plate attached to said Wehnelt cylinder, said holding plate having a plurality of guiding holes. 15

7. A Braun tube including a Wehnelt cylinder including at least one hollow cylindrical portion, a metallic cathode holder mounted inside said Wehnelt cylinder and having at least one cylindrical portion the outer diameter of which is equal to the inner diameter of said hollow cylindrical portion, said second mentioned cylindrical portion having its outer surface located adjacent to the inner surface of said hollow cylindrical portion for axially aligning said cathode holder with said Wehnelt cylinder, and a thermionic cathode 20 supported and positioned in said Wehnelt cylinder by and insulated from said cathode holder, said cathode having an emissive surface located symmetrically in relation to the axis of said second mentioned cylindrical portion, a metallic holding plate attached to said Wehnelt cylinder, said holding plate having a plurality of guiding holes, and a container containing a vaporizable metal, said container being attached to said Wehnelt cylinder by means of a short metal tube, 25 the inner space of said container communicating with the inner space of said cylinder through said metallic tube. 30

8. A Braun tube comprising a press, an envelope sealed to said press, a plurality of metallic 40 holders attached to said press, a Wehnelt cylinder including at least one hollow cylindrical portion, a metallic cathode holder mounted inside said Wehnelt cylinder and having at least one cylindrical portion the outer diameter of which is equal 45 to the inner diameter of said hollow cylindrical portion, said second mentioned cylindrical portion having its outer surface located adjacent to the inner surface of said hollow cylindrical portion for axially aligning said cathode holder with 50 said Wehnelt cylinder, and a thermionic cathode supported and positioned in said Wehnelt cylinder by and insulated from said cathode holder, said cathode having an emissive surface located symmetrically in relation to said second mentioned 55 cylindrical portion, and a metallic holding plate attached to said Wehnelt cylinder, said holding plate having a plurality of guiding holes, said Wehnelt cylinder being slipped over said metallic holders with the use of said guiding holes of said 60 supporting plate, at least one anode arranged in operative relationship to said cathode, a fluorescent screen, and two pairs of deflecting plates, said anode and said deflecting plates being attached to said metallic holders. 65
